UNITED STATES PATENT OFFICE

OLIVER C. DENNIS, OF WILMETTE, ILLINOIS

RADIO RECEIVER

Application filed October 10, 1927. Serial No. 225,213.

My invention relates to radio receivers and has for its broad object the provision of a radio receiver of simplified and improved construction and performance.

5 Radio receiving sets with single dial control have simplicity in handling which has made them very popular with the ultimate purchaser. The usual method of tuning such sets is by means of variable condensers and 10 most single dial sets have the condensers connected in a single "gang" so that they will all be turned together, thereby theoretically obtaining substantially the same capacity setting on each condenser. Considerable efficiency is lost in these old arrangements however, as it is a practical impossibility to construct a plurality of condensers having balanced capacities at each setting.

There are other faults to be found with the 20 usual present day commercial sets including the difficulty with which the parts are assembled, the relatively high cost expended unnecessarily on unimportant details, the inaccessibility of the various parts for repair purposes and the like.

Among the specific objects of the present invention is the provision of an improved single dial control for a plurality of variable condensers.

30 Another object is to produce a single dial control which may be quickly converted into a multiple control type.

Another object is to adjust the capacity of the condensers separately and without manipulation of the normal controlling element.

Another object is to provide means for adjusting the condenser stator plates to control the fixed capacity of a condenser and balance each condenser with its associated coil.

40 Another object is to provide an improved arrangement for supporting the apparatus.

Another object is to provide an improved tube supporting means.

Another object is to provide an improved 45 coil mounting.

Another object is to provide an improved panel assembly.

Other objects will be apparent from a consideration of the following detailed description 50 explaining the main features of the in-

vention and accompanied by the drawings, wherein—

Fig. 1 is a plan view of my improved receiver removed from its cabinet;

Fig. 2 is a fragmentary front elevational view thereof, showing the tuning arrangement on the front panel; 55

Fig. 3 is a sectional view taken along the line 3—3 of Fig. 1 and showing the control dial in elevation;

Fig. 4 is an enlarged plan view of a portion of Fig. 1;

Fig. 5 is a fragmentary vertical section taken along the line 5—5 of Fig. 4;

Fig. 6 is an elevational view looking at the 60 end of Fig. 4;

Fig. 7 is a section along the line 7—7 of Fig. 4;

Fig. 8 is a bottom plan view of the auxiliary panel; 65

Fig. 9 shows the wiring diagram;

Fig. 10 is a detail of the tube socket; and

Fig. 11 is a fragmentary section showing the coil mounting.

Reference may now be had to the drawings 75 wherein one embodiment of my invention is shown incorporating in a preferred form the features of the invention. The construction and arrangement of the various portions of the apparatus and the manner in which they 80 are combined results in a receiver which may be produced very economically but which nevertheless surpasses in tone quality selectivity and all around performance, other receivers which have come to my knowledge. 85

The receiver is provided with the usual front panel comprising a section or lamination metal 10 or other material substantially equivalent in strength and a decorative front face 11 preferably a fine grade of wood suitably secured to the metal panel 10 as by the use of screws 12. The front panel has secured thereto, a plurality of brackets 13—13 having a horizontal section to which is secured an auxiliary panel 14 preferably constructed of bakelite or an equivalent material. With the panels disposed in this position and employing the circuit which I use and which will be referred to more in detail hereinafter, the movable apparatus may be 100

mounted on the front panel for convenience of access during tuning, and the immovable or nonadjustable apparatus such as tubes, transformers, coils, fixed condensers and the like, are secured to the auxiliary panel. This immovable apparatus is so disposed on the panel that all of the wiring is accomplished on the reverse or bottom side thereof, so that the upper part of the panel is free of any obstructions and presents a clean flat, surface encumbered only by the apparatus. The circuit is so arranged that only a relatively small number of wires 16—16 extend between the two panels. These are made easily detachable if desired so that the two panels may be assembled separately during manufacture and then secured together by fastening the wires on condenser 16 in place. In the practical embodiment of these features, I have only six wires secured across between the two panels.

The apparatus mounted on the front panel, comprises a plurality of variable condensers 17—17 provided with the usual rotor and stator plates and have their rotor plate shafts 18—18 in alignment. As indicated, the condensers are arranged in pairs, two on each side of the panel, the rotor shaft being common to two condensers. The two rotor shafts have their contiguous ends almost abutting, and each of these shafts is provided with a hand wheel 19 through the operation of which the rotor shafts may be actuated to vary the capacity of the condenser. Normally, the two hand wheels 19 would be operable separately but a pin 21 is secured in suitably provided apertures in the wheels to fasten them together so that they and all of the condensers will turn together as a single unitary system.

The condensers as previously observed are mounted in pairs, each pair having end plates 22 secured to the panel 10 and having the rotor shafts 18 journaled therein. Each end plate has suitably secured thereto, a tension spring 23 adapted to bear against a shoulder (Fig. 4) provided on the rotor shafts for the purpose of holding the shafts against possible end play and supplying the requisite tension thereto.

Secured between each pair of end plates are three rectangular bars 24 to which the stator plates are adapted to be secured. The securing or fastening means is so constructed that the stator plates may be moved with respect to the rectangular mounting bars for the purpose of adjusting the capacity of each individual condenser.

Each set of stator plates 26 has secured thereto, a plurality of spacers 27, the construction of these spacers being preferably as disclosed in my co-pending application Serial No. 756,391, filed December 17, 1924. The spacers project slightly below the outside edge of the group of stator plates and

a mounting yoke 28 is frictionally secured to each one of these projections. The mounting yokes are provided on their outside ends with square apertures suiting them to be threaded onto the bars 24 in the manner shown. As a fastener for the mounting members 28, I provide a spring clip 29 articulated at its ends to engage the top or outside end of the mounting members 28 and having a slot substantially midway of its ends through which a machine screw 31 is adapted to extend to secure the spring clip 29 against movement. The construction is the same for each one of the spacers 27, there being a spacer on each group of stator plates for each one of the bars 24.

This construction permits the stator plates to be adjusted with respect to the rotor plate so that the capacity of a condenser may be modified. It is apparent that any one of the spacers may be slightly moved without substantial change in the adjustment of the other spacers and in this way the capacities of the various condensers may be made to coincide for the same setting.

As the drawing indicates, two of the spacers are located within easy access, being above and below the condenser but the third spacer is positioned against the panel so that normally it would be impossible to loosen the screw 31 to permit adjustment of this portion of the condenser. To obviate this difficulty however, a screw driver hole 32 is provided in the steel panel but not the face panel, so that during assembly and test of the receiver technicians may be able to make all of the adjustments required; but after the receiver is completed this hole is covered up so that it will not be within easy reach of the ordinary user.

Referring again to the hand wheels, each is provided with a graduated paper tape 33 secured thereon by suitably provided screws 34 and having graduations in kilocycles, meters or any arbitrary arrangement of numbers which might be desired. Each hand wheel is provided with a pair of stops 36—36 adapted to strike the panel and prevent complete rotation of the condensers. These stops are so arranged that they serve as a support for the tapes, as such tapes may be hooked under the stops while they are being placed on the face of the wheels and before the screws 34 are screwed into position. Since one stop strikes the upper part of the panel to limit the turning and the other strikes the lower part, it is apparent that the pin 21 will never be within reach from the front of the panel and that for all ordinary purposes, the usual operator of the set will be apt to be content with the "gang" operation of the condenser. It is apparent that if a perfect balance is obtained, this is all that is necessary but inasmuch as after careful adjustment, there may be slight difference due to the difference in

tubes and the like, the "2 in one" feature may have some advantage when tuning in on a distant station where the signals are somewhat weak.

Any suitable system of current control may be employed with the present receiver but good results have been obtained by the use of the rheostat. The circuit is arranged so that a single rheostat will control the current input to the radio frequency and detector tube while the fixed resistance is provided for the audio tube. The rheostat is mounted on the front panel so the rheostat knob 37 is positioned near the bottom of the escutcheon plate and immediately below the condenser control.

Attention may now be directed to the rear or auxiliary panel to which the immovable portions of the apparatus are secured. In Fig. 1 the top of the auxiliary panel is shown and is illustrated with coils 41—41 secured on the upper face thereof with suitable tubes 42 and a grid leak 43 resiliently held between suitable terminals. Binding posts 44 at the left of the panel provide means for connecting the receiver into the operating electrical circuit, some of the wires so secured to these posts being adapted to extend to a source of current, the other binding posts leading to the aerial and ground wires.

Instead of employing the conventional type of tube socket, a novel arrangement is provided whereby the auxiliary panel itself serves as a portion of the socket and a better result is obtained than by the use of the usual sockets, the contacts and all the wires incidental thereto, being kept below the panel. In the provision of this arrangement, a number of holes are formed in the panel, one for receiving each one of the terminal lugs 46 at the base of the tube. This is a total of four holes for each tube and they are arranged in clusters of four in convenient places on the panel so as to obtain the spacing arrangement shown. Immediately adjacent to each hole is a terminal contact 47 of spring material secured by a rivet 48 to the underside of the panel. Each one of these terminal contacts is provided with a portion 48^a adapted to closely abut the contact lug on the radio tube when the lug is extended through the hole in the panel and has an angularly disposed projection 48^b to which a wire conductor forming a part of the circuit is soldered.

The coils 41 are also secured to the panel through a novel arrangement which produces a much better and more economical structure than any heretofore known. The coils have a hollow insulating core 51 to the upper part of which is secured a secondary winding 52, while a primary winding 53 is coiled around the bottom of the core in alignment with the secondary winding. Near the base of the hollow core, terminals 54 are secured by means of rivets 56, these terminals being four in

number and connected to the ends of the coils. Four holes through the panel are adapted to receive the terminals which project to the underside of the panels through these holes and are bent over in the manner illustrated in Fig. 11, to secure the coil in an immovable position on the panel. The bent-over ends of the terminals serve as connections to which proper wire conductors forming a part of the circuit are soldered. In this way it will be observed that the same terminal strip serves three functions, namely as a terminal for the coils, as a securing means for fastening the coil core to the panel and as a terminal for interconnecting the conductor and the coils.

Fig. 9 shows a circuit which is particularly well adapted for use with the improvement forming a part of my radio receiver. As shown, the circuit includes six tubes and is of the tuned radio frequency type. There are three stages of radio frequency, a detector and two transformer coupled audio stages. In the radio frequency stages and first audio, I employ a CX301A tube or equal; for the detector CX300A or equal and for the second audio a CX112 or equal.

With this hook up embodied in a receiver having the features described and shown, I am able to get exceptional selectivity with the unit control balanced coils and paired condensers and without employing the "2 in one" feature, which however may improve reception at certain times, as for instance when tuning in a distant station.

What I claim as new and desire to secure by United States Letters Patent is as follows:

1. In a radio receiver, a front panel, a pair of variable condensers secured on the reverse side of said panel and having their rotor plate shafts in alignment, a pair of hand wheels each secured to one of said shafts and positioned side by side with a portion of their arcs extending through the panel for turning the same, and a quickly removable pin extending through the two hand wheels causing them normally to be operated in unison but adapted to be removed to permit independent adjustment.

2. A radio receiver as defined in claim 1, with a pair of stops carried by the wheels, said removable pin being between the stops so that the back of the panel will have to be exposed in order to remove the pin.

3. A radio receiver as defined in claim 1, with a pair of stops carried by the hand wheels, said wheels also adapted to have indicator tapes and said tapes guided into position by said stops.

4. In a radio receiver, a plurality of condensers with their rotor plate shafts in alignment and connected for turning by a single dial, a plurality of bars for supporting the stator plates thereon, a plurality of spacers for the stator plates adjacent the bars, and a

ing members secured to the spacers and threaded on the bars, a spring clip adapted to engage each pair of mounting members to secure them in immovable position on the bars, and fastening means extending through the clip and engaging the bar for securing the clip to the bar, an elongated slot being provided in the clip to permit movement thereof longitudinally of the bar so that the stator plates may be adjusted sidewise.

5. In a radio receiver, a plurality of condensers with their rotor plate shafts in alignment, a plurality of bars for supporting the stator plates thereon, a plurality of connections from the stator plates to the bars adapted to be slidable thereon, spring clips for engaging the connections to secure them in immovable positions on the bars, fastening means extending through the clips and secured to the bars for securing the clips thereto, an elongated slot being provided in the clips to permit movement thereof longitudinally of the bars, a plurality of hand wheels one on each rotor shaft contiguously placed and having aligned apertures therein, and a removable pin for engagement in the apertures to lock the hand wheels together for unit operation of the condensers.

In witness whereof, I hereunto subscribe
30 my name this 2nd day of September, 1927.

OLIVER C. DENNIS.
